UNITED STATES PATENT OFFICE

RUDOLPH M. SANDERS, OF NEW YORK, N. Y., ASSIGNOR TO ADARTCRAFT, INC., OF NEW YORK, N. Y., A CORPORATION OF DELAWARE

DISPLAY DEVICE

Application filed June 13, 1930. Serial No. 460,931.

This invention relates to display devices and more particularly to an embossed member adapted to be arranged in a package or container to simulate the top row of articles normally packed in the container so as to create the impression that a full container of merchandise is being displayed. In the copending application of August Mayer, Serial No. 407,949, filed November 18, 1929, (now Patent No. 1,786,253, granted Dec. 23, 1930) the provision of an embossed member arranged in a container to simulate the top row of articles normally packed in the container is described and claimed. The invention is particularly suitable for the display of cigars due to the practically universal custom in the merchandising of cigars of displaying open boxes of the product.

At the present time a number of brands of cigars are sold with the individual cigars placed in a wrapper of cellophane or other transparent wrapping material. I have found that if a layer of cellophane is placed over the embossed member of the Mayer invention there is not sufficient excess material at the ends to properly simulate the folded (or twisted) ends of the cigar wrappers and that the Mayer invention is therefore not applicable to the display of individually wrapped cigars.

In accordance with my invention I space the embossed sections simulating the individual cigars on the sheet and then fold the unembossed sections of the sheet or mat to bring the individual embossings adjacent each other. This folding of the unembossed sections of the sheet gives the appearance of greater depth, so that relatively shallow embossed sections in combination with the folded sections, more closely simulate a layer of the genuine articles. The folded sections also provide spaces into which strips of fluted paper may be tucked to give, for example, the appearance of a layer or row of individual candies, each in its own individual paper cup. In order to truly simulate a layer of candies, it is frequently necessary to cover some of the embossed sections with foil, and the folded sections of the sheet provides space into which the edges of the foil may be

tucked. In other instances, notably in forming imitation layers of cigars, I then assemble the embossed member on a support having spaced slots adapted to receive the folded portions of the mat. This not only increases the strength of the embossed mat, due to the additional material, but it permits the cellophane or other transparent material to be tucked into the slots and affords sufficient excess material at the ends to simulate the folded or gathered ends of the packages in which the individual cigars are sold.

The invention further comprises a method and means for folding the cellophane to simulate the folded or gathered ends of the wrappers.

In the accompanying drawings I have shown several forms of the invention. In this showing,

Fig. 1 is a perspective view of a cigar box showing the embossed member in the position normally occupied by the top row of cigars;

Fig. 2 is a transverse, vertical, sectional view of the cigar box shown in Fig. 1 showing the cellophane or other transparent wrapping material arranged to simulate folded ends;

Fig. 3 is a view similar to Fig. 2 showing the support folded for reception in a smaller box and also showing the cellophane or other wrapping arranged to simulate "twisted" or gathered ends;

Fig. 4 is an enlarged plan view of the mat showing the arrangement of the cellophane after it has been tucked in position between the folded sections of the mat, parts being broken away to show the construction of the support;

Fig. 5 is a transverse, vertical, sectional view of a portion of the support and mat;

Fig. 6 is an end view of a portion of the support and mat showing the ends of the cellophane wrapping or covering;

Fig. 7 is a detailed, sectional view of the end of one of the individual embossings diagrammatically illustrating the apparatus used for simulating the folded ends in its initial position;

Fig. 8 is an end view of the cellophane wrapping;

Fig. 9 is a view similar to Fig. 7 after the apparatus has assumed an intermediate position;

Fig. 10 is an end view of the cellophane in the position corresponding to Fig. 9;

Fig. 11 is a view similar to Fig. 9 showing the folding step near its completion;

Fig. 12 is an end view of the cellophane in Fig. 11;

Fig. 13 is a view at the end of the folding operation;

Fig. 14 is an end view of the cellophane in Fig. 13 of the drawings;

Fig. 15 is a view similar to Fig. 6 showing the projecting portions of the cellophane slit for simulating twisted or gathered ends;

Fig. 16 is a sectional view of one of the individual embossings showing the apparatus employed in this step in its initial position;

Fig. 17 is an end view of the parts shown in Fig. 16;

Fig. 18 is a view similar to Fig. 16 showing the parts in an intermediate position;

Fig. 19 is a view similar to Fig. 18 showing the parts at the end of the operation; and

Fig. 20 is an end view of the individual embossing and cellophane wrapping with a twisted or gathered end.

Referring to the drawings, the reference numeral 1 designates generally the usual cigar box having a hinged lid 2. The embossed member simulating the top row of cigars is indicated generally by the reference numeral 3. It is adapted to rest on a support 4 arranged just below the level of the top of the box and supported in position by upright or inclined members 5. The details of the construction of the support form no part of the invention and any conventional construction can be employed for this purpose. It is the custom to merchandise cigars in boxes consisting of alternate rows of twelve

and thirteen cigars and in a box of fifty cigars they are arranged in four rows. Fig. 2 illustrates the invention applied to a box of this size. A box 6 of the proper size for twenty-five cigars is shown in Fig. 3 of the drawings and the display device forming the subject matter of the present invention can be used with a box of this size by scoring the supporting members 5 on lines 7 and folding the lower portion 8 of the support into the position illustrated in Fig. 3 of the drawings.

As stated in the Mayer application, the mat is provided with a plurality of adjacent embossed sections representing or simulating individual cigars. In carrying out the present invention, I take a mat and emboss it to simulate individual cigars at spaced points 9. The support 4 is provided with a plurality of spaced slots 10 and the unembossed intermediate sections of the mat are adapted to be folded into these slots as indicated at 11 in

Fig. 5 of the drawings. By spacing the individual embossings in this manner the additional material provided gives greater stretch during the embossing operation and therefore a greater depth of impression and, in addition, the appearance of even greater depth than it actually possesses so that the spaced individual embossings is a distinct improvement even when the covering or wrapper of cellophane or other transparent material is not used. It also gives the appearance of even greater depth than it actually possesses.

As shown in Fig. 4 of the drawings the bands placed on cigars of many makes may be simulated as indicated at 12. Either individual bands may be placed over the individual embossings and secured thereto as by gluing or in any other suitable manner or a strip may be prepared embodying the sections of bands

that are normally visible when the cigars are packed in a box and this strip may be secured to the embossed member 3. After the strip has been placed in position a sheet 13 of cellophane or other transparent wrapping material is placed over the embossed member and tucked into the slots 10 as indicated at 14. In some instances the bands 12 or the strip representing the bands is placed on the embossed member after the cellophane covering.

As shown in Fig. 4 of the drawings, the support is of less width than length of a cigar so that the ends of the individual embossings project beyond the support at the front and back of the box. The folded portions 11 of the mat are preferably cut away at the ends as indicated in dotted lines in Fig. 4 of the drawings. Thus, the end of the individual embossed members and the end portions of the cellophane project beyond the support. When the cellophane is first tucked in position, the exposed end assumes substantially the outline shown in Figs. 6 and 8 of the drawings with the bottom of the loop widened as indicated at 15.

In simulating folded ends I employ a pair of members 16 and 17, the upper member being of greater thickness than the lower member and being recessed to receive the lower member providing an overhanging lip 18. These members may be mounted in any suitable reciprocating holders or may be moved by hand as indicated in Figs. 7 to 13 of the drawings. As the lower member moves upwardly the loops 15 are flattened out as indicated at 19. At that time the lip 18 of the upper member engages the upper surface of the cellophane as indicated in Fig. 11 of the drawings and the end of the cellophane assumes the shape or outline 20 indicated in Fig. 12 of the drawings. Upward movement of the lower member 16 is arrested but the upper member 17 continues to move downwardly with the lip 18 in front of the lower member and the cellophane between the two as indicated in Fig. 13 of the draw-

ings. The resulting end is indicated in Fig. 14 of the drawings wherein the cellophane is folded in a substantially straight line 21 along the edges of the individual embossings 5 and is provided with several thicknesses at the points 22 between the tapered ends of the cigars. The excess material indicated at 23 may then be arranged under the ends of the cigars as indicated at 24 in Fig. 2 of the drawings. The result is that in the spaces 25 between the tapered ends of the cigars (see Fig. 4) several thicknesses of the cellophane are provided which give an appearance very similar to that of the individually wrapped 10 cigars. The several thicknesses of material create the same reflection and refraction of light that is obtained with cigars when they are individually packaged and thus permits the use of the embossed imitation row of 15 cigars in the merchandising and display of individually wrapped cigars.

Referring to Figs. 15 to 20 of the drawings in simulating the gathered or twisted ends of the sheet of cellophane is first cut at the bottom of each loop 15 providing depending portions 26. In this operation three reciprocating members are used, a lower member 27 and upper members 28 and 29. Each of these members is of substantially the same 20 construction as shown in Fig. 17 of the drawings and is provided with a V-shaped portion 30 having a notch or recess 31 at the bottom of the V. As shown in Fig. 18 of the drawings the members are first reciprocated in 25 unison toward the cellophane or other material to be gathered and the walls 30 of the V-shaped portions engage the cellophane and gather it in. When the reciprocating members have reached a position with the bottom 30 of each of the V-shaped openings in engagement with the cellophane, the lower member 27 and one of the upper members 28 stop moving. The outer upper member 29 continues downwardly as shown in Fig. 19 of the 35 drawings. The cellophane over the end portion of the cigars is thus drawn through the restricted space formed by the walls of the slots or notches 31 in the reciprocating members 27 and 28 and is drawn downwardly by 40 the outer reciprocating member 29 to the position shown in Fig. 20 of the drawings forming the "twisted" or gathered end 32. The excess material is slightly spaced from the 45 embossed member 9 as shown in Fig. 20 of the drawings thus creating the impression of an individually wrapped cigar.

I claim:

1. A display device comprising a support and an embossed sheet comprising a plurality of spaced embossings representing articles to be displayed, the unembossed portions of the sheet being folded under the surface to dispose said embossings adjacent each other.
2. A display device comprising a support

having a plurality of spaced slots, and an embossed sheet comprising a plurality of spaced embossings, the unembossed portions of the sheet being adapted to be folded into said slots to dispose said embossings adjacent each other. 70

3. A display device comprising a support having a plurality of spaced slots, an embossed sheet comprising a plurality of spaced embossings, the unembossed portions of the sheet being adapted to be folded into said slots to dispose said embossings adjacent each other, and a transparent sheet covering said embossings and fitting into said slots. 75

4. A display device comprising a support having a plurality of spaced slots, an embossed sheet comprising a plurality of spaced embossings, the unembossed portions of the sheet being adapted to be folded into said slots to dispose said embossings adjacent each other and a transparent sheet covering said embossings and fitting into said slots, the ends of said transparent sheet being folded to simulate the ends of individually wrapped articles. 80

5. The method of simulating the folded ends of individually wrapped cigars which comprises providing a covering of transparent material having excess material at each end, and flattening said excess material to simulate folded ends. 95

6. The method of simulating gathered ends of individually wrapped cigars which comprises providing transparent material covering the cigars and projecting beyond the ends thereof, and gathering the projecting end portions of said material by means of reciprocating members having V-shaped slots formed therein. 100

7. An embossed sheet having a plurality of spaced embossings representing individual articles to be displayed, the unembossed portions of the sheet being folded to dispose said embossings adjacent each other. 105

8. A display device comprising an embossed sheet representing a plurality of articles to be displayed, said sheet having folded unembossed portions between the embossed portions, and a sheet of covering material arranged over said embossings and tucked between said folded unembossed portions. 110

9. A display device comprising a member representing a row of articles, the individual representations being slightly spaced from each other, and a covering sheet of transparent material covering said representations and tucked into the spaces between them. 120

10. A display device comprising a sheet having a plurality of representations of articles to be displayed formed thereon and slightly spaced from each other, and a sheet of transparent material covering said representations and tucked into the spaces between them. 125

11. The method of simulating the folded ends of individually wrapped articles which comprises arranging a sheet of transparent material over a member representing a row of the articles to be displayed with excess material at each end of the articles, and flattening said excess material to simulate folded ends;
12. The method of simulating the gathered ends of individually wrapped articles which comprises arranging a sheet of transparent material over a member representing a row of the articles with excess material at each end of the articles, slitting the excess material between each pair of articles and gathering the slit portions.

In testimony whereof I affix my signature.

RUDOLPH M. SANDERS.
